SHEARS

Gerald Wilson, Pelham Manor, N. Y.

Application October 9, 1943, Serial No. 505,598

10 Claims. (Cl. 30—267)

This invention is an improvement in shears, and by that term I include all apparatus or constructions for domestic, manicure, industrial, or other purposes, and in which two pivotally connected members have edges, one of which is progressively moved past the other to sever any article or material or portion thereof projecting between said edges. These pivotally connected members hereinafter referred to as blade members, may each move in respect to the other, as for instance in ordinary shears, scissors, hedge trimmers, or other analogous devices, or one which may be stationary and the other movable about the pivotal connection.

Both of the cutting edges may be substantially straight or curved more or less away from each other, or curved in the same direction and to the same or different extents, or one may be straight and the other convexly curved. Either or both of the blade members may be, and preferably are, slightly curved toward the other, so that they are pressed together with the proper pressure at the cutting point at all positions of the cutting point along the length of the cutting edges.

The invention relates more particularly to the means employed for holding the cutting edges in yielding engagement with each other throughout the length of the cut.

I am aware that it has been proposed to use a spring at the pivotal connection and that it has also been proposed to use a spring fulcrumed at said pivotal connection and bearing on a ball mounted in one blade and movable along the other in a path at a short distance behind said connection.

Where one or more balls have been used, they have been held in sockets so that they could not roll along the blade member which carried them; or in constructions where they could roll along said member, they have not been yieldingly pressed toward the other member by any spring or other resilient member.

The present invention involves a new principle and method of operation with shears, and the main object of the invention is to provide means exerting pressures or forces tending to cant the blade members toward each other from the pivotal connection, and which pressures and forces are in perfect equilibrium or balance irrespective of changing angles between said members during the cutting operation.

In carrying out the invention, means are provided which tend to press the blade members apart at two spaced points in the rear of the pivot, and thus press the blades together at a

third point, namely, the point of cutting. These three points define a triangle, within which is the pivotal connection between the blades. Thus the forces applied tend to tilt the blades in the direction of their length but do not exert any tendency to tilt the blades laterally at any time during the movement of the blades in respect to each other.

As an important feature, the pressure or force exerted at the first mentioned two points is through balls, roller members, or other elements which may travel transversely of the blade member carrying them, as well as transversely of the other blade member, as the blades move in respect to each other during opening and closing of the shears. Thus, the three points are at all times so positioned that a line from the cutting point through the pivot falls between the other two points. Preferably, this line bisects the angle between the two lines drawn from the cutting point through the other two points where pressure is applied.

The balls, roller members, or other elements are spaced apart and maintained at substantially equal distances from the pivot. Thus, they may roll along on both blade members, and travel through angular distances equal to one-half the angular distance of the blades during any given relative movement of the blades. They remain spaced to the same distance in all normal relative positions of the blade members and thus the base of the triangle defined by the three pressure points is kept of substantially constant length.

As a further feature, a spring or other resilient means is employed, and which is of such a character and so positioned that equal pressure is exerted at both of said two points and at all times during the transverse movement of said points in respect to either blade. Thus, the pressure of one blade against the other at the cutting point is properly maintained and the blades cut as effectively at one end of the cutting movement as at the other.

As a further feature, the balls or other roller members travel in separate grooves or slots, which extend in a generally arcuate direction and substantially concentric with the pivot. They may be in separate arcs of the same circle but may depart slightly from true arcs and may be along short tangents to said arcs. As the balls in said grooves or slots travel at the same rate, they are maintained at all times at substantially symmetrical position in respect to a line from the cutting point through the pivot.

From the standpoint of manufacture, it is in

some respects preferable that both grooves or slots defining the path of movement of the balls be in the same blade member, although from the standpoint of operation, it is entirely satisfactory to have one groove or slot in one blade member and the other in the other blade member.

In the accompanying drawing:

Fig. 1 is a view in elevation showing shears embodying my invention, certain details being shown in dotted lines.

Fig. 2 is a side elevation, a portion being shown in section,

Fig. 3 is a plan view of a portion of one of the blade members,

Fig. 4 is a view similar to a portion of Fig. 1, but showing a portion of the upper blade member broken away and the shears in closed position.

Fig. 5 is a view similar to Fig. 4, but showing the shears open to about 30°.

Fig. 6 is a view similar to Figs. 4 and 5, but showing the shears open to about 90°.

Fig. 7 is a view similar to Fig. 3, but showing the slots of slightly modified form.

Fig. 8 is a section through the shears in the direction of the length of the slot and on a very much enlarged scale,

Fig. 9 is a transverse section through the parts shown in Fig. 8, and

Figs. 10, 11 and 12 are diagrammatic views showing the relative positions of the cutting point and the two rear pressure points with the blade members in the positions shown in Figs. 4, 5 and 6, respectively.

In the construction illustrated, I have shown shears which may be of any standard shape, form, or design, except as hereinafter described, and which comprises a pair of blade members 10 and 11 connected by a pivot member 12 and having handles 13 and 14. The pivot member is shown as a simple screw with a head countersunk in the blade member 10 and a shank threaded into the blade member 11. The shear members have cutting edges 15 and 16, respectively, which may move past each other to form a cutting point A, which moves progressively along the length of the cutting edges as the shears are opened and closed.

One of the blade members here illustrated as the blade member 11 is provided with a pair of grooves 17 and 18 in the flat face thereof, which is directly opposed to a flat face of the other blade member and in the rear of the pivot; that is, in the portion of the blade members opposite from the cutting edges and in respect to the pivot.

The two grooves are shown in Fig. 3 as being along separate arcs concentric with the point B, which is the axis of the pivot member 12. It is not essential that these grooves be exactly concentric or curved because they may be straight, as shown at 17a and 18a of Fig. 7, in which case the grooves are chords of the arcs. Ordinarily, the grooves extend along about 50° or 60° of the circle around the center point B and the length will ordinarily be determined by conditions hereinafter referred to. If the shears are to open about 90°, then one end of the groove 17 should be directly in the rear of the pivot point B and one end of the groove 18 should be at approximately 90° from said end of the groove 17, but this angular displacement will vary according to the angle to which the shears may normally be opened. The two grooves are spaced apart end-

wise and both lie on the same side of a diameter passing through the point B.

In each groove there is mounted a roller member here shown as a ball 20. The ball projects somewhat beyond the face of the shear member 11 in which the groove is formed and contacts with the opposed face of the shear member 10. Suitable means are employed for yieldingly pressing the ball into engagement with the surface of the shear member 10, and thus tending to separate the shear members at the rear of the pivot and thereby press the shear members toward each other along the portions having the cutting edges. As shown, a spring 21 extends lengthwise of each groove along the bottom thereof and has a trough or channel 22 forming a track or runway for the ball. The sides of the groove may be parallel, but preferably they are made slightly diverging, as shown in Fig. 9, to facilitate the cutting of the groove and the removal of the spring member, should any replacement be necessary.

When the shears are in closed position, each ball will normally be at one end of its groove; these ends being the ends farthest around the circumference in the same angular direction and as illustrated in Fig. 4.

By reason of the spring or other yielding means, the two balls exert a pressure against the blade member 10 and the pressure will thus be exerted at two spaced points C and D, which are disposed on radii from the point B, making equal angles with the main center line of the blade. As the shears are opened, the balls will travel along their respective grooves at the same rate and through angular distance equal to one half the angle between the center lines of the blades. Thus, when the blades have been separated to 30°, the balls will have moved through 15° along their grooves, and when the shears are opened to 90°, the balls will move through 45°. As the balls move at equal rates and at rates proportional to the relative movement of the blades, the spacing between the balls will remain constant. As one blade exerts pressure on the other at the cutting point A, and as the balls exert pressure at the points C and D, these three points form a triangle, which, in the embodiment shown, is a symmetrical isosceles triangle. The pivot point B is within the triangle referred to and is preferably on the center line of the triangle.

Fig. 10 is a diagram showing the position of the pressure points A, B and C in respect to the pivot point B, and it will be noted that the line AB is a bisector of the angle CAD. As the cutting point A will move toward the pivot point B during the opening of the shears, the same geometric relationship will exist. Fig. 11 shows the angle between the cutting edges substantially 30°, and Fig. 12 shows what may be the extreme position with the angle between the cutting edges substantially 90°. Thus, the three points at which pressure of one blade is exerted on the other are symmetrically arranged and the two pressure points C and D are on opposite sides of and at equal distances from the line from the pressure point A to the fulcrum point B.

If the maximum opening between the cutting edges is 90°, then each groove should extend along 45° plus an amount equal to the diameter of the ball. Obviously, if the shears are to open to a greater or lesser extent, the grooves should be correspondingly longer or shorter. The shears may be provided with any suitable stop limiting

the opening of the blades to an amount determined by the length of the grooves.

In the construction shown, the grooves 17 and 18 are shown as separate grooves. Obviously, in commercial manufacture, these may be formed as a single groove and a block, stop, or partition be secured intermediate of the ends of such single groove to, in effect, form two separate grooves. It will be noted that each ball is at the same distance from the pivot point B, as is the other ball, regardless of the positions of the balls in their travel along the grooves, and this applies when the grooves are along chords of arcs as shown in Fig. 7, as well as when along arcs, as shown in Fig. 3. These grooves are shown as extending only part way through the wall of the blade member, but obviously they might extend all the way through and constitute slots, provided that there be a suitable guideway or support for the roller member which moves therealong.

As shown, the two grooves 17 and 18 are formed in the same blade member and therefore are non-symmetrically disposed in respect to the center line of the blade. One groove may be formed in one blade member and the other in the other blade member, in which case the grooves would be symmetrically disposed in respect to the general length of the blades when in closed position. Where the cutting edges 15 and 16 are straight or are curved to the same extent and away from each other, the line AB will bisect the angle CAD, but if one blade be straight and the other curved, or if the two cutting edges curve in the same direction, the line AB will not necessarily bisect the angle CAD in all operating conditions, but it is important that the points C and D at all times be upon opposite sides of the line AB.

By means of my invention there is provided more perfect operation of the shears; the cutting blades are always maintained in contact, the proper pressure is exerted on the cutting blades at the cutting point, regardless of the position of the latter, the pressure is applied at three points spaced apart around the pivotal center, the pressure in the rear of the pivot point is applied at spaced points on opposite sides of the line from the pivotal center to the cutting point, and the distance between the rear pressure points is maintained substantially constant irrespective of varying angles between the blades.

Having thus described my invention, what I claim as new and desire to secure by Letters Patent is:

1. Shears having two blade members, each presenting a cutting edge, a connecting pivot member whereby said members have relative swinging movement to progressively move the cutting point along said members to different distances from said pivot member, a pair of spaced elements between said blade members at the opposite side of said pivot member from the cutting point and slightly spacing said blade members apart, and means whereby said elements are maintained at substantially equal distances apart and upon opposite sides of and at equal distances from a line intersecting said pivot member and said cutting point when said blade members are in all normal cutting positions.

2. Shears having two blade members, each presenting a cutting edge, a connecting pivot member whereby said members have relative swinging movement to progressively move the cutting point along said members to different distances from said pivot member, and a pair of spaced elements

between said blade members at the opposite side of said pivot member from the cutting point and slightly spacing said blade members apart, each of said elements being movable in respect to both of said blade members and at angular velocities in respect to said pivot substantially equal to one-half the angular velocities of said blade members during relative movement of said blade members.

3. Shears having two blade members, each presenting a cutting edge, a connecting pivot member whereby said members have relative swinging movement to progressively move the cutting point along said members to different distances from said pivot member, and a pair of spaced elements between said blade members at the opposite side of said pivot member from the cutting point and slightly spacing said blade members apart, each of said elements being movable in respect to both of said blade members in arcs substantially concentric with said pivot and at angular velocities substantially equal to one half the angular velocities of said blade members during relative movement of said blade members.

4. Shears having two blade members, each presenting a cutting edge, a connecting pivot member whereby said members have relative swinging movement to progressively move the cutting point along said members to different distances from said pivot member, and a pair of rollers slightly spacing said blade members apart and upon opposite sides of an extension of a line through said cutting point and said pivot, each of said rollers being movable along both of said blade members during relative movement of the latter.

5. Shears having two blade members, each presenting a cutting edge, a connecting pivot member whereby said members have relative swinging movement to progressively move the cutting point along said members to different distances from said pivot member, a pair of rollers slightly spacing said blade members apart and upon opposite sides of an extension of a line through said cutting point and said pivot, each of said rollers being movable along both of said blade members during relative movement of the latter, and means for applying yielding pressure to said rollers tending to tilt the blade members likewise and to press them together at the cutting point.

6. Shears having two blade members, each presenting a cutting edge, a connecting pivot member whereby said members have relative swinging movement to progressively move the cutting point along said members to different distances from said pivot member, said shears having a pair of grooves spaced apart endwise, spaced from said pivot member at the side of the latter farthest from the cutting point and extending in a general direction of tangents to a circle having said pivot member as a center, and roller members, one disposed in each of said grooves and movable along the grooves as said shears are opened and closed.

7. Shears having two blade members, each presenting a cutting edge, a connecting pivot member whereby said members have relative swinging movement to progressively move the cutting point along said members to different distances from said pivot member, one of said shear members having a pair of grooves spaced apart endwise, spaced from said pivot member at the side of the latter away from the cutting point and extending in a general direction of tangents to a circle having said pivot member as a center, said grooves being non-symmetrically disposed in respect to

the general center line of said blade, and a pair of roller members, one disposed in each of said grooves and movable along the grooves as said shears are opened and closed.

8. Shears having two blade members, each presenting a cutting edge, a connecting pivot member whereby said members have relative swinging movement to progressively move the cutting point along said members to different distances from said pivot member, said shears having a pair of grooves spaced apart endwise, spaced from said pivot member at the side of the latter farthest from the cutting point and extending in a general direction of tangents to a circle having said pivot member as a center, roller members, one disposed in each of said grooves and movable along the grooves as said shears are opened and closed, and means exerting a yielding pressure on said roller members and tending to press said blade members together at the pivot point.

9. Shears having two blade members, each presenting a cutting edge, a connecting pivot member whereby said members have relative swinging movement to progressively move the cutting point along said members to different distances from said pivot member, one of said shear members having a pair of grooves spaced apart endwise, spaced from said pivot member at the side of the latter away from the cutting point and extending

in a general direction of tangents to a circle having said pivot member as a center, said grooves being non-symmetrically disposed in respect to the general center line of said blade, a pair of roller members, one disposed in each of said grooves and movable along the grooves as said shears are opened and closed, and means exerting a yielding pressure on said roller members and tending to press said blade members together at the pivot point.

10. Shears having two blade members, each presenting a cutting edge, a connecting pivot member whereby said members have relative swinging movement to progressively move the cutting point along said members to different distances from said pivot member, said shears having a pair of grooves spaced apart endwise, spaced from said pivot member at the side of the latter farthest from the cutting point and extending in a general direction of tangents to a circle having said pivot member as a center, roller members, one disposed in each of said grooves and movable along the grooves as said shears are opened and closed, and a pair of springs, one operating in each groove and pressing each roller member toward the other blade throughout the length of the movement of the roller member along the groove.

GERALD WILSON.
